(57) **CLAIM**

The ornamental design for a lamp device, as shown and described.

DESCRIPTION

FIG. 1 is a perspective view of a lamp device showing our new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom plan view thereof;

FIG. 8 is a longitudinal cross-sectional view thereof taken along the lines VIII—VIII in FIG. 6;

FIG. 9 is a front view thereof showing a state in which the lamp body is tilted around a horizontal axis;

FIG. 10 is an illustrative perspective view of the lamp device according to our new design received in a receptacle shown in broken lines for illustrative purposes only; and,

FIG. 11 is another illustrative perspective view of the lamp device of our new design received in a receptacle and attached with a light reflector each of which are shown in broken lines for illustrative purposes only and forming no part of the claimed design.
